(57) **CLAIM**

The ornamental design for a holding clamp, as shown and described.

DESCRIPTION

FIG. 1 shows a top view of the holding clamp in accordance with the invention.

FIG. 2 shows a side view of the holding clamp.

FIG. 3 shows a front view of the holding clamp.

FIG. 4 shows a perspective top view of the holding clamp.

FIG. 5 shows a perspective bottom view of the holding clamp.

FIG. 6 shows the holding clamp, thin wall, and retaining clip separately.

FIG. 7 shows the holding clamp, thin wall, and retaining clip in the assembled state.

FIG. 8 shows the holding clamp in connection with a disassembly tool; and,

FIGS. 9 and 10 show a cross-sectional view and a perspective view, respectively, of the holding clamp engaging with the disassembly tool.

The broken lines in the figures represent environment only and form no part of the claimed design.
